UNITED STATES PATENT OFFICE

MARCH F. CHASE, OF ARDSLEY-ON-THE-HUDSON, AND FREDERIC E. PIERCE AND JOHN SKOGMARK, OF NEW YORK, N. Y., ASSIGNEES TO THE COS PROCESS COMPANY, INC., OF NEW YORK, N. Y., A CORPORATION OF NEW YORK

MAKING PRODUCER GAS

Application filed August 10, 1920, Serial No. 402,718. Renewed March 29, 1928.

The object of our invention is to provide a practical and economic process of manufacturing producer gas of greater calorific power than hitherto produced as well as to provide the apparatus requisite for carrying on such process, and the invention also has other incidental objects and advantages all of which will be made apparent in the following description.

10 Briefly stated the invention contemplates the operation of the gas producer in the usual way and with substantially the usual reactions except that in place of some or all of the air ordinarily used, a special gaseous mixture is admitted to the combustion zone, such mixture containing less nitrogen and other inert gases, and more oxygen than air and thereby serving to make a producer gas with a low percentage of nitrogen and other diluents and therefore with a high content of heat units. The invention further contemplates the diversion and use of a small part of the rich gas thus produced for the manufacture of the said special mixture, 15 which is done in a continuous cycle and in such manner as to derive power as a by-product of said manufacture, which power is available for driving the blower or blowers or other purposes incident to operation 20 25 30 of the process.

Figures 1 and 2 respectively illustrate the plan of the apparatus and the cycle of its operation.

In Fig. 1, we illustrate the process diagrammatically. The gas producer (1) receives the coal or carbonaceous material to be gasified and may be assumed to be an ordinary type of producer. The gas passes to the assembly of necessary purification apparatus which is called the scrubber and marked (2) and, passing through which, the gas will be cooled and tarry matters and other objectionable impurities removed. The larger part of the gas is thence passed by 45 the valve 3^a to the delivery pipe 3 leading to its place of storage or consumption. The remainder normally bearing a constant ratio to the delivery, is retained in the circuit and passed to a combustion device 5 where it 50 is utilized to do work. Such device may be

the burner of a boiler or furnace or an internal combustion engine or its equivalent and is here assumed to be an engine and to be used for driving the blower 7 for maintaining the circulation of the gases. The 55 producer gas delivered to it may be enriched, when and as necessary, by admitting oxygen, or an oxygen-containing gaseous medium through the valve 4^a from a source 4 and the combustion products of this device are drawn 60 through a gas cooler 6 by the blower or gas pump 7 and from the latter pass by pipe 9 to the producer, but in transit thereto they are enriched by a further amount of oxygen admitted through the valve 4^b from the oxygen source 4, thereby, forming the special 65 gas producer operating mixture above referred to. A by-pass 10 from the outlet of the blower serves to return more or less of the products of combustion, with the oxygen gas medium added to them, to the combustion apparatus, according to the setting of its valve 10^a, thereby providing a means for regulating the flow to the producer as well as the flow to the device 5, or engine. 70 A boiler 8 furnishes and controls the amount of steam necessary for the operation of the gas producer, and other usual appurtenances to producer systems may be assumed to be present. 75

In the common processes of producing gas from coal and carboniferous material, air is ordinarily forced by a steam jet, through an incandescent bed of the fuel. Under such conditions the gas produced consists 85 principally of carbon monoxide (CO) hydrogen (H₂) with smaller quantities of marsh gas (CH₄) and other hydrocarbons as combustibles, with carbon dioxide (CO₂) and nitrogen (N₂) as the principal diluents, 90 the nitrogen carrying with it small percentages of argon and other inert gases derived from the air used in the process. The mixture of air and steam forced into the bed of fuel in the producer brings about several 95 chemical inter-reactions resulting in a gas generally analyzing about as follows, for example: CO—20% to 25% : H₂—8% to 12% : CH₄ etc. 2% to 4% : CO₂—4% to 8% : with 100 O₂ and N₂ and other hydrocarbon gases, mak-

ing up the balance to 100%. Such a gas will have a calorific value between 125 to 150 B. t. u. per cubic foot. The large percentage of N_2 and diluents, necessarily present in the producer gas, because of the air used in its production, and the ever present CO_2 , limit the calorific power so that it rarely exceeds 150 B. t. u. per cubic foot.

In the operation of our system above outlined the producer reactions occur from the combination of the carboniferous material and steam with a gaseous mixture, constituted of the combustion products of the device 5 which are supplemented or enriched by the addition of oxygen as stated. Such a mixture may possibly contain some elements having a fuel value depending on the manner of operation of the said device and will of course contain CO_2 and some nitrogen but these diluent and substantially inert components will constitute a less percentage than the percentage of inert gases ordinarily entering the producer when it is operated by air. The proportion is under control by regulation of the amount of oxygen added or by regulation of the percentage of oxygen present in the source 4, the result being that the reactions are more efficiently conducted and the generated gas far richer in heat units than could otherwise be the case. The oxygen addition may be derived from any suitable source, several inexpensive methods being known to the art and available for the purpose. It is of course unnecessary that it be pure, any oxygen-containing gaseous medium of fairly high oxygen content being suitable.

The various valves shown, and others where necessary, and also the blower, which may be of variable speed, and its by-pass furnish the means whereby the gas producing operations are regulated and controlled. The blower or gas pump may obviously be located at any point in the system where it will maintain the gas flow as desired and according to the kind of system and apparatus in which the invention is used, and moreover its functions may be performed by several blowers as desired.

In the operation of the plant, temperatures are taken and samples of the gases at the several stages of the process from time to time, and analyses of these samples are made. The temperatures and analyses can be easily taken care of, if desired, by the well known automatic recording machines. The constituents of the gases at the several stages of the process obviously determine the adjustments to be made and it will be noted that the cycle of operations is a continuous process which can be controlled as a whole as well as in respect to its individual steps or stages.

Figure 2 is a simplified illustration of a typical gas cycle according to this invention.

Carbon is charged into the gas producer at the rate of 10 lbs. per minute. This is gasified by 184.07 cu. ft. of gas mixture per minute forced into the producer together with 2 lbs. of steam per minute, this being 20 per cent of the weight of carbon charged. The total amount of gas produced is 412.21 cu. ft. per minute containing 332.11 cu. ft. (80.5%) of carbon monoxide, 44.18 cu. ft. (10.7%) of hydrogen and 35.92 cu. ft. (8.8%) of nitrogen. Such a gas has a theoretical heat value of about 310 B. t. u. per cubic foot according to the cycle illustrated and will of course be recognized as superior in calorific value to present day products. 90 per cent of it is available for commercial purposes and 10 per cent is recirculated and used in the process. The portion retained for circulation is mixed with the oxygen gas medium from the source 4, containing, for example, 80 per cent, of oxygen. The amount of this medium required is 161.67 cu. ft. per min. containing 129.34 cu. ft. of oxygen and 32.33 cu. ft. of nitrogen and other inert diluents. All of this may be mixed with the recirculated portion and passed through the combustion apparatus or only a part of it, as circumstances may require. The by-pass effects the necessary division if only a part is used, the balance being added to the products of combustion. If a 10 per cent portion of the total gas product is mixed with a part or all of such addition of oxygen gas medium and used in an internal combustion engine, assuming an efficiency of 30%, there would be developed about 83 engine horse power for blower-driving or other purposes. The heat of the exhaust of the engine or device 5 may also be used for heating the feed water to the boiler 8, in any suitable way, not illustrated. The products of the combustion in device 5 consists of 33.21 cu. ft. per minute of carbon dioxide and 4.42 cu. ft. of water vapor mixed with the 3.59 cu. ft. of nitrogen in the recirculated portion and the 32.33 cu. ft. in oxygen gas mixture amounting together to 35.92 cu. ft., the excess oxygen amounting to 110.52 cu. ft. per minute, and the products of combustion with the uncombined balance of the added oxygen-containing medium amounting as previously stated to 184.07 cu. ft. per minute. Preferably the combustion products of the device or engine 5, will contain not over 55% N_2 and at least 45% CO_2 , and after mixing with oxygen, not over 70% of N_2 or less than 15% CO_2 , nor less than 10% O_2 . It has been assumed in the case illustrated that 10% of the total gas product is used for circulation through the combustion device 5, but this amount may be from 5% to 35% (when corrected for temperature) without impairing the economies and depending upon the manner of utilization of the power derived from the

combustion. At the cooler 6 the temperature is preferably less than 100° C.

It is evident that in practice the gas cycle may be exceedingly complex depending on the character of the fuel used, the speed of operation and the inevitable variations in the work from time to time. However the basic conditions and limitations governed by fuel, speed of operation and the character of the product required will govern any particular instance and these will not vary.

All of the necessary adjustments for continuous and even working, as we have already explained, can be made under any given set of conditions and the process can be applied to obtain results surpassing any that have hitherto been possible.

Having thus described our process it will be seen that we have disclosed a continuous process for the manufacture of producer gas by circulating gases through a cycle of operations, with means for controlling and regulating the volume, temperatures and constituents thereof, which results in a gas product of high calorific value and which by controlling the percentage of the oxygen-containing addition may be made of the greatest possible calorific value.

While we have described above the particular embodiment of our invention which we consider gives the most advantageous results, it should be understood that we do not mean to limit ourselves to that exact process or to the identical steps described nor to all of such steps, since obviously many changes may be made therein without departing from the spirit of our invention, the principle of which has now been explained.

Claims—

- 40 1. In the manufacture of producer gas, a continuous process for the production of gas of greater calorific power than 150 B. t. u. per cubic foot by continuously passing gases through a cycle of operations consisting of gas producing, diverting a portion of the gas for storage or use, the remainder being of predetermined volume and constituents, and when corrected for temperature being between 5% and 35% of the volume of gas leaving the gas producer and containing not over 55% N₂ and not less than 45% of CO, mixing the same in such volume and of such constituents, with a predetermined amount of free oxygen or a gaseous medium having a higher content of free oxygen than air, utilizing the energy of said mixture by burning said mixture in a combustion unit, and using the combustion products for making more gas.
- 60 2. In the manufacture of producer gas, a continuous process for the production of gas of greater calorific power than 150 B. t. u. per cubic foot by continuously passing gases through a cycle of operations consisting of gas producing, diverting a portion of the

gas, mixing the remaining portion with oxygen, the gases being of predetermined volume and constituents at the mixing stage, being not over 55% N₂ and at least 45% CO₂ and at such stage having added to them a predetermined amount of free oxygen or a medium with a higher content of free oxygen than air and after such mixing operation containing not over 70% of N₂ nor less than 15% CO₂, nor less than 10% O₂, and using said mixture in making producer gas.

3. In the manufacture of producer gas, a continuous process of producing gas of greater calorific value than 150 B. t. u. per cubic foot, which consists in continuously passing a gaseous mixture through a gas producer, diverting a substantially constant major portion of the produced gas to a place of storage or use, circulating the remainder through a path leading back to and through the gas producer and a combustion unit, thereby developing power and products of combustion, introducing into said path of circulation a substantially constant amount of free oxygen or gaseous medium having a higher free oxygen content than air, and utilizing said developed products of combustion in the operation of said gas producer.

In testimony whereof we have signed this specification.
